UNITED STATES PATENT OFFICE.

CASPER D. WALLACE, OF BRIDGEPORT, CONNECTICUT, ASSIGNOR TO THE YOST WRITING MACHINE COMPANY, OF ILLION, NEW YORK.

TYPE-WRITING MACHINE.

SPECIFICATION forming part of Letters Patent No. 661,628, dated November 13, 1900.

Application filed November 3, 1897. Serial No. 657,278. (No model.)

To all whom it may concern:

Be it known that I, CASPER D. WALLACE, a citizen of the United States, and a resident of Bridgeport, in the county of Fairfield and State of Connecticut, have invented certain new and useful Improvements in Type-Writing Machines, of which the following is a specification.

The primary object of my invention is to provide a construction by which the platen may be separated or detached from the platen ratchet-wheel, which forms a part of the line-spacing mechanism, in order that the platen may be turned independently of said ratchet-wheel in either direction to any desired extent, whereby ruled paper, date-lines, and other especially-prepared portions of a sheet, such as blank spaces and the like, may be brought quickly and conveniently to the printing plane or point by merely turning the platen instead of seizing the paper by the hands and pulling it backward or forward for the purpose of adjusting the same upon the platen and bringing the place to be impressed to the printing-point before commencement of the writing.

My invention consists in the features of construction and combinations of devices hereinafter more fully described, and particularly pointed out in the appended claims.

In the accompanying drawings, Figure 1 is a plan view of a portion of the carriage of a "Yost" type-writing machine and embodying my improvements. Fig. 2 is a right-hand end view thereof, omitting the line-spacing lever or rock-shaft and the line-space regulator. Fig. 3 is a detail view, on a large scale, of the clutching devices. Fig. 4 is a side view of the same. Fig. 5 is a longitudinal central vertical section through the carriage and the platen and looking from the rear and showing the parts in their normal conditions. Fig. 6 is a view similar to Fig. 5, but showing the conditions of the parts when the ratchet-wheel and platen are separated for independent rotation of the latter. Fig. 7 is a vertical section taken at the line $x-x$ of Fig. 5. Fig. 8 is a similar section taken at the line $y-y$ of Fig. 6, and Fig. 9 is a perspective view of the device 18.

In the various views the same parts will be

found designated by the same numerals of reference.

1 designates the platen carrier or frame, which may be of any desired construction 55 and which in this example is pivotally attached at its rear side to a yoke or sliding carriage 2, provided with a feed-rack 3, as usual. 4 designates a cylindrical platen which is supported to turn within said frame. In 60 this instance the platen comprises a hollow cylindrical core 5, preferably of wood, and an outside covering or sheath of rubber 6; but the platen may be otherwise constructed. At the left-hand end of the platen (when in the 65 machine) is a head of metal consisting of a cylindrical hub or bearing 7, a cylindrical flange 8, and a cylindrical shank 9. The hub 7 passes within the core and supports the same, while the flange 8 sits up close to the 70 end of the platen and is attached thereto by dowels or pins 10, which enter the core longitudinally. The outwardly-projecting shank 9 is hollowed out centrally, as at 11, to receive a fixed stud or pivot 12, projecting inwardly from the left-hand end bar 13 of the platen-frame, and mounted exteriorly upon said shank is a hand-wheel 14 for turning the platen and which may be knurled or roughened to facilitate its action. 8c

15 is a rod having at its left-hand end (when in the machine) a head 16, which is seated in the housing 11. The rod passes through a perforation in the shank 9 and hub or bearing 7, and, extending nearly the full length of the 85 platen, is threaded at its opposite end, as at 17, to engage a threaded hole in a connecting, supporting, and clutching device, (designated as a whole by the numeral 18.) The device 18 comprises a circular flange 19, which bears 90 against the right-hand end of the platen, a cylindrical hub or bearing 20, which enters the platen-core, and a cylindrical hollow stem or socket 21, provided in this instance with an adjustable end piece or nut 22. The threaded 95 end of the rod engages the adjustable piece 22, which is threaded exteriorly to engage interior threads in the tube or socket 21, and with a boss 23, which enters the nearest coils of a spiral spring 24 within said socket, the opposite end of the spring being seated in a cup-shaped device or plunger 25, adapted to slide 100

in the bore of the socket 21 and having a solid boss 26 at its outer end. By turning the rod 15 in the proper direction the heads or flanges 8 and 19 may be drawn or clamped against the ends of the platen 4 with any desired force. The said device 18 also comprises an integral collar or circular shoulder 27 forward of the flange 19, and in front of the part 27 is a circular ledge or bearing 28, from which extends forwardly an integral hollow cylindrical hub or bearing 29.

On diametrically-opposite sides the collar or shoulder 27 is preferably flattened, as at 30, and through these portions of said collar are formed slots or openings 31 radially of the axis or bore of the device for the introduction and accommodation of the shanks 32 of two segmental friction devices 33, preferably formed of sheet metal. The inner free ends 20 of said shanks are slotted or forked, as at 34, to surround the inner end of a pin 35, which bears against the solid boss 26, and provided with a fixed collar or circular shoulder 36, which bears against the forked ends of the 25 said shanks 32 and confines the same on said pin between itself and the said boss.

Within the hub or bearing 29 is fitted a screw plug or bearing 37, which is perforated centrally, as at 38, to form a bearing for the 30 pin 35 to slide in axially of the device 18 and of the platen. The said screw-plug has an exterior thread, which is screwed into an interior thread in the end bar 39 of the platen carrier or frame 40.

35 Externally of the flange 19 and preferably fitting the same snugly is a platen ratchet ring or wheel 41, having in this case teeth 42 on its side, adapted to be engaged by a driving-pawl 43 on a rock-shaft 44, having an actuating-handle 45, as customary in the Yost machine, and the said ratchet-wheel has also in this instance a series of seats or depressions 46 around its periphery, adapted for the usual spring-pressed holdfast-roller 47; but as far 40 as the main features of my invention are concerned some other form or construction of ratchet-wheel may be employed instead of that herein shown and described. The said ratchet-wheel is also formed on its outer side 45 with a circular flange 48 in a plane at right angles to its axis, and the said flange is adapted to a circular seat or ledge 49 on a ring 50, which itself is seated on the bearing or hub 28 and is held pressed against the face or 50 front side of the collar 27 by means of three screws 51, the shanks of which pass through holes in the said ring 50 and into tapped holes 52 in the side of the hub or bearing 28, the heads of the screws overlapping the side of 55 the ring 50, and thus holding it firmly in position.

60 The edges of the segments 33 fit or conform to the circular interior surface of the ratchet-wheel, as shown, and are adapted to press outwardly against the same, as indicated at 53, and by such pressure or friction connect the said ratchet-wheel with the device 18,

which in turn is positively connected to the platen, preferably by means of pins 54, secured at diametrically-opposite points to the 70 flange 19 and entering holes or sockets formed in the ends of the core 5 of the platen. Thus the device 18 is so attached to the platen as that it always turns therewith, and the ratchet wheel or ring is so connected to the platen as 75 that it also normally turns therewith, the connection being effected through or by means of the segmental friction devices, which have a toggle-like action under the pressure of the coiled spring 24. The said spring acting on 80 the solid boss 26 and the latter acting on the shanks of the segmental clutches, the clutch devices are straightened out or brought into substantially the same vertical plane, whereby the edges of the segments are forced outwardly or radially against the interior surface of the ratchet-wheel, thereby producing sufficient friction to enable the ratchet-wheel 85 to turn the platen through said clutching devices and the device 18 when the said ratchet-wheel is turned by the line-spacing pawl. The outward pressure of the spring 24 to produce the desired friction of the clutches is 90 limited or resisted by the sliding pin 35, the outer end of which abuts against the upturned end 55 of a lever 56, which is pivoted at 57 on the under side of the end bar 39 and which is provided at its forward end with a thumb-piece or handle 58 and with a lip or projection 59, which bears against the said end bar 100 39, and thus prevents any movement of the said lever, and hence the sliding pin under the pressure of said spring.

95 In the positions of the parts at Fig. 5 the clutches are in frictional engagement with the ratchet-wheel, and hence when said wheel is turned by the line-spacing mechanism the platen is caused to rotate therewith through the intermediate devices hereinbefore described; but when the parts are in the positions shown at Fig. 6 the platen is adapted to be turned by the hand-wheel 14 or otherwise independently of the ratchet-wheel, which may then remain stationary and which will be held perfectly still by the pressure-roller 110 47. The parts are brought into the positions shown at Fig. 6 by pressing the finger-piece 58 outwardly or in the direction of the arrow at Fig. 1, thus causing the upwardly-projecting end 55 of said lever to force inwardly the 115 sliding pin 35, and thereby break the toggle-joint or cause the edges of the segments to recede from the surface of the ratchet-wheel, in this action the collar 36 pressing upon the shanks of the segments and forcing them inwardly and the end of the sliding pin forcing the slide 25 in the same direction and causing a compression of the coiled spring. As long as the sliding pin 35 is held pressed in and the clutches are out of frictional engagement with the ratchet-wheel the platen 120 may be rotated freely without turning said wheel, and hence the platen may be moved through either long or short arcs or revolved 125 130

to any desired extent in either direction for bringing the ruled lines or blank spaces on the printed matter to the printing-point. When the actuating-lever 56 is released the 5 coiled spring 24 immediately forces out the sliding pin and at the same time causes the toggle-levers or segmental clutches to again straighten out to the position shown at Fig. 5 and again frictionally engage the ratchet- 10 wheel, so as to restore it into operative relation with the platen. In practice the edges of the segments may be moved only a very minute distance in order to effect the disengagement of said ratchet-wheel from and its 15 reengagement with the platen or, what is the same thing, to release the platen from the ratchet-wheel or the line-spacing mechanism and again connect it therewith.

What I claim as new, and desire to secure 20 by Letters Patent, is—

1. In a type-writing machine, the combination of a platen, a ratchet-wheel, a detent therefor, a clutch, a spring, operating normally to hold said clutch in frictional engagement 25 with said ratchet-wheel, and means adapted to be actuated by the hand of the user for overcoming the pressure of the spring and releasing the clutch so as to enable the platen to be turned independently of the ratchet- 30 wheel while the hand of the user is overcoming the pressure of the spring.

2. In a type-writing machine, the combination of a platen, a ratchet-wheel, a detent therefor, a clutch, a spring, operating normally 35 to hold said clutch in frictional engagement with said ratchet-wheel, a sliding pin opposing said spring, and means for moving said pin to overcome the pressure of the spring and release the ratchet-wheel, whereby the platen 40 may be turned independently of the ratchet-wheel and the clutch.

3. In a type-writing machine, the combination of a platen, a ratchet-wheel, a detent therefor, a clutch, a spring operating normally 45 to hold said clutch in frictional engagement with said ratchet-wheel, a sliding pin, and a lever for actuating said pin.

4. In a type-writing machine, the combination of a platen, a ratchet-wheel, a detent therefor, 50 a pair of clutching-segments arranged within said ratchet-wheel, a sliding pin connected to said clutching-segments, a spring operating normally to hold the said segments in frictional engagement with the interior of 55 said ratchet-wheel, and means for sliding said pin and disengaging said clutching-segments from said ratchet-wheel.

5. In a type-writing machine, the combination of a platen, a flanged hollow stem or 60 socket secured to one end of said platen and having a collar or shoulder as 27, a ratchet-wheel loosely mounted on the flanged part of 65 said device, a detent for said ratchet-wheel, a pair of segments having shanks which pass through slots or openings in the collar or shoulder, a sliding pin or rod connected to the inner ends of said shanks a spring within

said socket, and a slide pressed thereby against said pin.

6. In a type-writing machine, the combination of a platen, a hollow stem or socket secured to one end of said platen by a flange 19 and having a bearing at 20 for said platen, a collar or shoulder as 27, a ledge as 28, and a hub as 29, a ring as 50, a ratchet-wheel mounted on said flange 19 and said ring 50, a detent for said ratchet-wheel, a pair of segmental clutches having each a shank which is accommodated in a slot or opening in said collar or shoulder, a sliding pin or rod connected to the inner ends of said shanks, a coiled spring within said socket, a plunger pressed outwardly by said spring, and means for moving the pin inwardly against the pressure of said spring. 85

7. In a type-writing machine, the combination of a platen, the device 18 secured thereto and comprising the flange 19, the bearing 20, the socket 21, the slotted collar 27, the ledge 28 and the hub 29, a ring as 50 seated on said ledge, a ratchet-wheel seated on said flange and on said ring, a detent for said ratchet-wheel, a plug or bearing as 37 for said hub, a pin or rod as 35 supported in a perforation in said plug or bearing, a pair of segments 95 having shanks which pass through the slots in the collar 27 and are connected to the inner end of said pin or rod, a coiled spring within said socket pressing outwardly against said pin or rod and said shanks and thereby 100 causing the said segments to frictionally engage with said ratchet-wheel, and means for forcing the said pin or rod inwardly against the pressure of said spring so as to release such frictional engagement. 105

8. In a type-writing machine, the combination of a platen, a socket secured within the core thereof and containing a coiled spring, a loosely-mounted ratchet-wheel, a detent therefor, and a pair of clutching devices carried by the socket device and held normally in frictional engagement with said ratchet-wheel by the pressure of said spring. 110

9. In a type-writing machine, the combination of a platen, a socket secured within the 115 core thereof and containing a coiled spring, a loosely-mounted ratchet-wheel, a detent therefor, a pair of clutching devices carried by the socket device, and held normally in engagement with said ratchet-wheel by the 120 pressure of said spring, and means for overcoming the pressure of the spring and releasing said clutching devices.

10. In a type-writing machine, the combination of a platen, a socket device secured within 125 the core thereof and carrying at its outer end a pair of clutching devices, a ratchet-wheel mounted upon said socket device, a detent for said ratchet-wheel, a spring within the latter for acting on said clutching devices to cause 130 them to frictionally engage said ratchet-wheel, and a slide for also acting on said clutching devices to break their engagement with said wheel.

11. In a type-writing machine, the combination of a platen, a head attached at one end thereof and comprising the hub 7, flange 8 and hollow shank 9, a hand-wheel mounted on said shank, the stud or pivot 12 on the end bar seated within said hollow shank, a flanged socket attached to the platen at its opposite end and extending within the core thereof, the threaded rod 15 connecting the said socket with the said head, a ratchet-wheel mounted loosely on said flanged socket, a detent for said ratchet-wheel, a spring-pressed clutching mechanism carried by said socket and operating to normally connect said ratchet-wheel with said platen, a sliding pin for freeing said ratchet-wheel, and means for moving said pin.

12. In a type-writing machine, the combination of a platen, a line-space ratchet-wheel, a detent therefor, means for rotating said ratchet-wheel, a platen-head carrying a clutch adapted to engage said ratchet-wheel, a spring acting normally to effect such engagement, a sliding pin for closing said spring, and means, independent of the platen, for moving said pin against the pressure of the spring to release said ratchet-wheel and permit the platen to be turned in either direction.

13. In a type-writing machine, the combination of a platen, a line-space ratchet-wheel, a detent therefor, means for rotating the ratchet-wheel, a platen-head, a clutch carried thereby and normally frictionally engaging said ratchet-wheel, a spring-pressed plunger mounted within said head and abutting said clutch, and a sliding pin to coact with said plunger.

14. In a type-writing machine, the combination of a platen, a platen-head secured at one end thereof, a line-space ratchet-wheel, hav-

ing a plunger and engaging said head, a detent for said ratchet-wheel, a pair of clutching-segments having shanks that are inserted within said head, a spring-pressed plunger abutting said shanks, a sliding pin opposing said plunger, and a lever for actuating said pin.

15. In a type-writing machine, the combination of a platen, a platen-head provided with a socket interiorly of said platen, a spring-pressed plunger within said socket, a line-space ratchet-wheel loosely mounted on said head, a detent therefor, means for rotating said ratchet-wheel, and a clutch comprising two segments carried by said head and held normally in frictional engagement with said ratchet-wheel by the pressure of said plunger.

16. In a type-writing machine, the combination of a platen, a platen-head provided with a socket interiorly of said platen, a spring-pressed plunger arranged within said socket, a line-space ratchet-wheel loosely mounted on said head, a detent therefor, means for rotating the ratchet-wheel, a clutch comprising two segments carried by said head and held normally in frictional engagement with said ratchet-wheel by the pressure of said plunger, and means independent of said plunger for overcoming the pressure thereof to release the clutch and permit the platen to be rotated in either direction independently of the ratchet-wheel.

Signed at Bridgeport, in the county of Fairfield and State of Connecticut, this 1st day of November, A. D. 1897.
